UNITED STATES PATENT OFFICE.

CARL J. DEXTER, OF LAFAYETTE, INDIANA.

ADHESIVE WAFER.

1,410,555.

Specification of Letters Patent. Patented Mar. 28, 1922.

Application filed November 24, 1920. Serial No. 426,236.

To all whom it may concern:

Be it known that I, CARL J. DEXTER, a citizen of the United States, residing at Lafayette, in the county of Tippecanoe and 5 State of Indiana, have invented certain new and useful Improvements in Adhesive Wafers, of which the following is a specification.

This invention relates to adhesive wafers 10 and more especially to an adhesive wafer which is intended to be employed in the mounting of photographic prints either upon card mounts or upon the leaves of an album, although the wafer is not restricted to this use.

Ordinarily in mounting photographic prints, adhesive is applied to the back of the print either over the entire surface thereof or a portion of the surface, and even where 20 the work is performed in a skillful manner there is liable to be a subsequent curling or warping of the print and the card or sheet upon which it is mounted. Also, where photographic prints are mounted in 25 an album, it is desirable at times to remove one or more of the prints but where they are mounted in the usual manner it is practically impossible to accomplish this without either marring the print or mutilating 30 the leaf upon which it is mounted because of the direct union of the surfaces of the print and mount. At the same time it is desirable that a photographic print be so mounted that it will retain a flat position 35 upon the surface of its mount. In consideration of the foregoing it is one of the objects of the present invention to provide an adhesive wafer which may be conveniently employed in mounting photographic 40 prints or the like and which will serve to retain the mounted print in a flat condition and will yet not so immovably secure the print as to result in curling or warping of the print or its mount.

45 Another object of the invention is to provide an adhesive wafer for the purpose stated which, while it is adapted to securely mount a print or the like, will nevertheless be so constructed as to permit of the print 50 or the like being readily removed from its mount whenever required without the necessity of mutilating either the print or the mount therefor.

55 A further object of the invention is to provide an adhesive wafer which may be manufactured at an exceptionally low cost

from a strip of material coated evenly upon one side only with an adhesive so that the employment of special machinery for applying adhesive to the strip or blank 60 over certain definite areas only, is obviated and the cost of manufacture correspondingly reduced.

In the accompanying drawings:

Figure 1 is a perspective view illustrating 65 one of the adhesive wafers embodying the invention applied at one of its surfaces to a mount, the photographic print which is to be secured upon the mount having one of its corners turned back to illustrate the 70 manner in which the wafer is arranged prior to the securing of this corner;

Figure 2 is a view similar to Figure 1 but illustrating the manner in which the print may be removed from the mount without 75 mutilation;

Figure 3 is a plan view of the blank from which the wafer is formed;

Figure 4 is a detail sectional view taken along a diagonal line through the print 80 and its mount and illustrating the manner in which the wafer is designed to secure the parts together.

In the drawings the numeral 1 indicates a photographic print which is to be applied 85 to the surface of a mount 2 which may be in the nature of a card or which may be the leaf of a photographic album.

The wafer embodying the invention is indicated in general by the numeral 3 and the 90 said wafer, as illustrated in Figure 3 of the drawings, is to be formed from a rectangular blank of material such for example as paper which blank is preferably of a length equal to substantially twice its width. This 95 blank is provided upon one of its faces with an adhesive coating 4 which extends over the entire area of the face, and after the blank has been prepared, it is to be folded along the dotted lines 5 in Figure 3 so as 100 to produce the completed wafer. It will be observed by reference to the said figure that the lines 5 extend from opposite corners of the blank to a point midway between the ends of one longitudinal edge of 105 the blank, and because of the relative proportions of the width and length of the blank, these fold lines extend at an angle of forty five degrees to either longitudinal edge of the blank.

While adhesive is applied, 110 as above stated, to one face only of the blank, it will be evident that when the

Blank is folded along the dotted lines 5, the wafer thus produced will have a triangular form and both the faces thereof will present an adhesive surface.

- 5 After the blank has been formed by folding it along the dotted lines 5 so that it assumes the right angle triangular form shown in Figure 1 of the drawings, it is to be moistened upon one side and applied
- 10 either to the under surface of the print or the upper surface of the mount to which the print is to be secured. In the former instance the closed edges of the mount will be brought into registration with the margin defining the selected corner of the print, the open side of the wafer being presented obliquely inwardly. Then upon moistening the other side of the wafer, the print may be laid upon the mount and secured thereto.
- 15 Inasmuch as the contiguous faces of the folded corners and the intermediate portion of the wafer blank are not secured together, the wafer may be extended slightly in the manner of a bellows, and consequently a
- 20 print which is secured by its four corners through the employment of the wafers, may expand and contract as may also its mount, without producing a warping or other distortion of either the print or mount. Fur-
- 25 thermore while a print may be secured by its four corners to its mounting surface through the employment of the wafers above described, the print may be readily removed from its mount whenever required by in-
- 30 serting a knife blade within the pocket of each wafer and slitting each wafer along its diagonal fold lines, as clearly illustrated in Figure 2 of the drawings, the folded corners of the wafer blank being left attached
- 35 to one of the previously connected members and the intermediate portion of said blank being left attached to the other member.

From the foregoing it will be evident that by employment of the adhesive wafer embodying the invention, a photographic print or the like may be mounted in a true flat

form equally as well and securely as though adhesive were applied to the entire surface area of the back of the same, and yet the print or the like may be readily removed 50 from its mount whenever required without the necessity of mutilating either the print or the mount.

While I have described above two different ways in which the wafers of the present 55 invention may be employed, it will be understood that they may also be applied by holding the print to be mounted firmly in place with one hand upon the face of the mount and then moistening both sides of the wafers 60 and positioning them beneath the corners of the print and subsequently pressing the corners down flat, and it is probable that this mode of application will be found most desirable and convenient.

Having thus described the invention, what is claimed as new is:

1. An adhesive wafer comprising a rectangular blank of a length substantially equal to twice its width, said blank being 70 folded along diagonal lines extending from the corners at one longitudinal edge to a point bisecting the opposite longitudinal edge thereby providing double layers, the exposed faces having an adhesive coating 75 for pasting two fibrous sheets together, said sheets being separable in intact condition by cutting the wafer along said diagonal lines between said layers.

2. A blank for an adhesive wafer, comprising a rectangular sheet having one entire side covered with an adhesive coating, two adjacent corners being folded together with the uncoated side inward, so as to form a two layered, right angle triangle with 85 both exposed faces coated for pasting two fibrous sheets together, said fibrous sheets being separable in intact condition by cutting the folded edges of the wafer.

In testimony whereof I affix my signature. 90

CARL J. DEXTER. [l. s.]
